C. PARADIS

ILLUMINATING DEVICE

Filed July 17, 1923

Charles Paradis ^{Inventor}

By William Clinton

Attorney

UNITED STATES PATENT OFFICE.

CHARLES PARADIS, OF MONTREAL, QUEBEC, CANADA.

ILLUMINATING DEVICE.

Application filed July 17, 1923. Serial No. 652,174.

To all whom it may concern:

Be it known that I, CHARLES PARADIS, subject of the King of Great Britain, residing at Montreal, in the Province of Quebec, 5 Canada, have invented certain new and useful Improvements in Illuminating Devices; and I do hereby declare that the following is a full, clear, and exact description of the invention, such as will enable others skilled 10 in the art to which it appertains to make and use the same.

This invention relates to improvements in illumination, having for an object to provide an improved illuminating device of the 15 flood type, particularly advantageous for use in the illuminating of townships, cities, etc., without the necessity of the usual street lamps and similar devices now prevalent.

It is also an object of the invention to provide 20 an illuminating device, which, in itself, will afford an ample source of light for the streets or other ways of a city, town or the like, during darkness, and which will reduce to minimum the presence of shadows with 25 the resultant absorption of night.

Other objects will be in part obvious and in part pointed out.

In order that the invention and its mode 30 of operation may be readily understood by persons skilled in the art, I have, in the accompanying 35 illustrative drawings, and in the detailed following description based thereon set out one possible embodiment of the same.

35 In these drawings:

Figure 1 is a perspective view of the improved device showing its mode of use;

Figure 2 is a fragmentary vertical longitudinal section through the same;

40 Figure 3 is a detail in elevation showing the relative arrangement of light sources or lamps and their respective reflectors within the device; and,

Figure 4 is a fragmentary transverse section 45 showing the manner in which the various lamps of the device are electrically interconnected.

Having more particular references to the drawings, in connection with which like characters of reference will designate corresponding parts throughout, the invention 50 may be stated to comprise a lamp casing or housing generally indicated by the numeral 1, formed of sheet metal or other suitable material and being of a proportion corre-

sponding to the area to be illuminated thereby. The forward end of the casing 1 is flared as at 2 and is open in order that the rays of light will be directed therefrom in divergent fashion and in consequence be directed over the area to be illuminated with maximum efficiency.

The housing 1 is preferably formed in sections, three in number, and include a rearward section 3, an intermediate section 4 and a forward or flared section 5, marginal flanges being formed upon each of these sections whereby to receive bolts or other suitable fastening devices, as indicated at 6 for securely or positively interconnecting the 60 juxtaposed sections. The intermediate section 4 carries bearing spindles 7 upon its opposite sides, which, in turn, are rotatably engaged in the opposite extremities of a bifurcated supporting bracket 8 having a dependent staff which rotatably receives therein a supporting post 9 arranged upon the platform of a tower 10 or similar elevated structure.

The rearward section 3 is formed with a 65 way which is of a size sufficient to admit an attendant or operator and is normally closed by means of a horizontal swinging door 11, a ladder 12 being preferably adjacent one side wall of the section 3 for obvious purposes. Upon the upper flared wall of the section 5, a plurality of transversely aligned shutter adjusting wheels 13 are mounted and have independent connection with shutters (not shown) arranged adjacent the upper 70 end of said section 5 whereby the transmission of light therefrom may be accordingly controlled.

The adjacent marginal portions of the sections 3 and 4 are formed with internal 75 flanges 14 which receive therebetween a wall 15, affording means for supporting a plurality of electric lamps 16 of extremely high candle power. Certain of these lamps 16 are provided with conical reflectors 17, 100 while those lamps intermediate the conical reflectors are provided with reflectors 18 which are substantially square in cross section. By this novel arrangement of reflectors 17 and 18, it will be appreciated that 105 the entire wall 15 will be provided with a reflecting surface for reflecting light rays emitted from their respective lamps 16 and thus, cause a projection of such rays forwardly from the flared open end of the sec- 110

tion 5 of the housing 1 over an area to be illuminated with maximum results.

Electrical conductors 19 are arranged in troughs or ways 20 upon the reverse side of 5 the wall 15 and, as will be understood, are accessible from within the section 3 of the housing 1, thus permitting of ready repairing of the lamps or their respective conductors as may become necessary.

10 As hereinbefore stated, the illuminating device is preferably arranged upon an elevated tower 10, this tower being provided with a ladder 21 to facilitate ascension thereon, while a platform 22 is arranged at its 15 upper end and communicates with the section 3 by way of another ladder 23. It is, of course, to be understood, in this connection, that the tower 10 is of a height which will permit the same to be arranged at a considerable 20 distance above the buildings within the city or town to be illuminated thereby, so that with energization of the various lamps 16, the light rays transmitted therefrom will 25 flood that area overlying the city or town and by consequence, certain of the rays from this illuminated area will be refracted in 30 their course of travel and will afford ample illumination for the streets of such city or town.

30 In order that the illumination of the city or town may be regulated, it is only necessary to adjust the shutter operating wheels 13, which wheels, in turn, will actuate their respective shutters in a manner to regulate 35 the supply of light in their particular zone corresponding thereto.

Manifestly, the construction shown is capable of considerable modification and such modification as is within the scope of 40 my claims, I consider within the spirit of my invention.

Having thus fully described the invention,

what I claim as new and desire to protect by Letters Patent is:—

1. A device of the character described 45 comprising an elevated structure, a housing adjustably supported on said structure, having a flared inward end, illuminating means within said housing, and individual reflectors for said illuminating means, certain 50 of which are conical and others of which are square and arranged intermediate said conical reflectors.

2. A device of the character described 55 comprising an elevated supported structure, a sectional housing adjustably supported thereon, having a flared open end, illuminating means arranged within the housing, and individual reflectors for said illuminating means, comprising conical and square reflectors, the square reflectors being arranged 60 intermediate the conical reflectors, as and for the purpose set forth.

3. A device of the character described 65 comprising an elevated structure, a sectional housing supported on said structure having a flared open end, a door way in the opposite end of the housing, the adjacent portions of said sections of the housing being flanged 70 to receive bolts therethrough, internal flanges formed on certain of the adjacent marginal portions of said sections, a wall supported between said internal flanges, a plurality of lamps arranged on said wall connected with a source of power, a plurality of conical reflectors for certain of said lamps, and a plurality of square reflectors for the remaining and intermediate lamps, said square reflectors being arranged rearwardly of and intermediate said conical reflectors. 75

In witness whereof I have hereunto set my hand.

CHARLES PARADIS.
